O. I. STRAUB AND M. WILDRICK.
BOMB OR SUBMARINE MINE.
APPLICATION FILED NOV. 6, 1917.

1,311,781.

Patented July 29, 1919.

UNITED STATES PATENT OFFICE.

OSCAR I. STRAUB AND MEADE WILDRICK, OF THE UNITED STATES ARMY.

BOMB OR SUBMARINE MINE.

1,311,781.

Specification of Letters Patent.

Patented July 29, 1919.

Application filed November 6, 1917. Serial No. 200,533.

To all whom it may concern:

Be it known that we, OSCAR I. STRAUB and MEADE WILDRICK, both of the United States Army, citizens of the United States, 5 stationed at Fort Adams and Fort Monroe, in the counties of Newport and Elizabeth City; and States of Rhode Island and Virginia, respectively, have invented certain new and useful Improvements in Bombs or 10 Submarine Mines; and we do hereby declare the following to be a full, clear, and exact description of the invention, such as will enable others skilled in the art to which it appertains to make and use the 15 same.

Our present invention relates to improvements in bombs for submarine mines which are intended to be dropped from the stern of a vessel, or from an air craft, and which 20 is exploded when the bomb reaches a predetermined depth.

The bomb is intended especially for use against submarines, and is intended to carry a large quantity of high explosive.

Our invention will be more fully understood after reference to the accompanying drawings, in which similar parts are indicated by similar reference symbols throughout the several views, and in which:

0 Figure 1 represents a complete bomb, parts being broken away;

Fig. 2 shows a section through the firing arrangement, the parts being shown on a much larger scale than in Fig. 1;

5 Fig. 3 shows an elongated projectile embodying the invention.

1 represents a shell of spherical or other desired form, and provided with a partition 2 separating the interior of the shell into two chambers. The chamber 3 is filled with the high explosive, and the chamber 4 is provided with one or more openings closed by the safety stoppers 5. Projecting down through this chamber 4, and into the chamber 3, is a tube 6 which is screwed into the partition 2, as at 7, and is closed at its lower end with a screw cap 8.

Supported on this cap 8 are the dry cells 10 which are contained in a chamber closed at its upper end by the partition 11, at some distance above which there is another partition 12 forming a chamber in which the detonating charge 13 is contained.

The tube 6 is provided with one or more openings 14, opening into the chamber 4, and is closed at its top with a screw cap

15, projecting from the center of which is the tube 16 which projects down through the partitions 11 and 12 and is closed at the bottom, as at 17. The said tube has 60 one or more openings 18 above the partition 12. At the lower end of the tube we provide electric circuit closers 19 connected to the electric primers 20, which are connected to the dry cells 10. 65

The upper end of the tube 16 is internally screw-threaded, as at 21, to receive the hollow stem 22 which is provided with a series of perforations 23, and is graduated, as at 24, to indicate the depth at which the bomb 70 is intended to operate. This stem is provided with hand lugs 25 for convenience in turning same. Inside of the hollow stem 22 we provide absorbent material 26, such as felt, wool, or the like, through which 75 water percolates.

The operation of the device is as follows:—

When in the safety position the stem should be screwed home, and the safety 80 stoppers should be in place, as shown in Fig. 2. When it is desired to launch the bomb turn the stem until the proper depth is indicated on the scale, then remove the stoppers 5 and drop the bomb overboard. 85 As it passes beneath the surface of the sea, water will flow into the chamber 4 and will pass through the openings 14 and 18, and, entering the openings 23, will flow through the absorbent material 26 and will ultimately 90 fill the chamber below the stem in the tube 16.

When this chamber becomes sufficiently full of water, ordinarily salt water, to complete the circuit through the circuit closers 95 19, the electric primers 20 will be ignited and the bomb will be exploded.

It will be noted that the farther up the stem is raised the more rapid will be the flow of water through the absorbent material 26, and the sooner will the electric circuit be closed. The stem is calibrated after the necessary experiments are made to determine the rate of flow of the water through the absorbent material corresponding to the position of the stem and the pressure of the water at various depths. 100

It will be seen that as long as the safety stoppers 5 are kept tightly closed no water can flow in, and the apparatus is absolutely 110 safe.

In the structure shown in Fig. 3, the

elongated projectile may either be flat nosed, as shown in full lines, or its nose may be pointed as shown in dotted lines.

It will be obvious that various changes 5 might be made in the herein described apparatus, and in the construction, combination and arrangement of parts which could be used without departing from the spirit of our invention.

10 Having thus described our invention what we claim and desire to secure by Letters Patent of the United States is:—

1. In a bomb, the combination with a shell provided with a main chamber adapted to 15 contain high explosive material, and a water chamber separable by a partition wall from said main chamber, and provided with one or more water inlets opening outward therefrom, with removable stoppers closing said 20 inlets, of firing mechanism for said bomb comprising a tube closed at its lower end and passing through said shell, and carrying a bursting charge, an electric battery, an electric primer connected thereto and 25 closed in said bursting charge, an inner tube having a flanged head screwed into the upper end of said first-mentioned tube, both of 30 said tubes being provided with one or more ports to admit water from said water chamber, a circuit closer mounted in said inner tube and connected to said primer, and an adjustable hollow stem provided with a 35 series of perforations, slidably mounted in said inner tube, and controlling the flow of water through the ports therein, substantially as described.

2. In a bomb, the combination with a shell provided with a main chamber adapted to 40 contain high explosive material, and a water chamber separable by a partition wall from said main chamber, and provided with one or more water inlets opening outward therefrom, with removable stoppers closing said 45 inlets, of firing mechanism for said bomb comprising a tube closed at its lower end and passing through said shell, and carrying a bursting charge, an electric battery, an electric primer connected thereto and 50 closed in said bursting charge, an inner tube having a flanged head screwed into the upper end of said first-mentioned tube, both of said 55 tubes being provided with one or more ports to admit water from said water chamber, a circuit closer mounted in said inner tube and connected to said primer, and an adjustable hollow stem provided with a series of perforations, slidably mounted in said inner 60 tube, and controlling the flow of water through the ports therein, with porous absorbent material mounted in said stem abreast of said perforations, substantially as described.

3. In a bomb, the combination with a shell

provided with a main chamber adapted to contain high explosive material, and a water chamber separable by a partition wall from 65 said main chamber, and provided with one or more water inlets opening outward therefrom, with removable stoppers closing said inlets, of firing mechanism for said bomb comprising a tube closed at its lower end 70 and passing through said shell, and carrying a bursting charge, an electric battery, an electric primer connected thereto and 75 inclosed in said bursting charge, an inner tube having a flanged head screwed into the upper 80 end of said first-mentioned tube, both of said tubes being provided with one or more ports to admit water from said water chamber, a circuit closer mounted in said inner tube and connected to said primer, said inner 85 tube being internally screwthreaded near its upper end, and a perforated hollow stem closed at the top and provided with screw threads engaging those on the inner tube, whereby said stem may be adjusted longitudinally, the said stem being provided with a series of perforations adapted to control the flow of water through the ports in the inner tube, substantially as described.

4. In a bomb, the combination with a shell 90 provided with a main chamber adapted to contain high explosive material, and a water chamber separable by a partition wall from said main chamber, and provided with one or more water inlets opening outward therefrom, with removable stoppers closing said 95 inlets, of firing mechanism for said bomb comprising a tube closed at its lower end and passing through said shell, and carrying a bursting charge, an electric battery, an 10 electric primer connected thereto and inclosed in said bursting charge, an inner tube having a flanged head screwed into the upper end of said first-mentioned tube, both of 10 said tubes being provided with one or more ports to admit water from said water chamber, a circuit closer mounted in said inner tube and connected to said primer, said inner 11 tube being internally screwthreaded near its upper end, and a perforated hollow stem closed at the top and provided with screw threads engaging those on the inner tube, whereby said stem may be adjusted longitudinally, the said stem being provided with a series of perforations adapted to control 1 the flow of water through the ports in the inner tube, with porous absorbent material mounted in said stem abreast of said perforations, substantially as described.

In testimony whereof, we affix our signatures.

OSCAR I. STRAUB.
MEADE WILDRICK.
